COMBINED ELECTRIC LIGHT BULB AND REFLECTOR THEREFOR

Fulvio Bossi, Milan, Italy

Application March 27, 1956, Serial No. 40,802

Term of patent 14 years

(Cl. D29—1)

Fig. 1

Fig. 2

Fig. 1 is a perspective view of a combined electric light bulb and reflector therefor showing my new design, and Fig. 2 is an elevational view thereof.

I claim:

The ornamental design for a combined electric light bulb and reflector therefor, substantially as shown.
